UNITED STATES PATENT OFFICE.

WILLIAM KIMMEL AND DANIEL KIMMEL, OF CAMBRIDGE CITY, INDIANA.

STUMP-EXTRACTOR.

Specification of Letters Patent No. 29,603, dated August 14, 1860.

To all whom it may concern:

Be it known that we, WILLIAM KIMMEL and DANIEL KIMMEL, both of Cambridge City, Wayne county, State of Indiana, have 5 invented a new and useful Stump-Puller; and we do hereby declare the following to be a full, clear, and exact description thereof, reference being had to the accompanying drawings, making part of this specification.

10 The subject of the said invention is a certain combination and arrangement of capstan, lever and movable roller for the purpose of applying a strong force for the "starting" of the stump and a more rapid 15 movement to complete its extraction as will be hereinafter explained.

In the accompanying drawings Figure 1 is a vertical section of a stump extractor embodying our improvement. Fig. 2 is a 20 perspective view of a detached portion of the same.

A is a portable frame in which the lifting devices are arranged. It is allowed to rest solidly upon the ground as shown when the 25 machine is in action, but has commonly attached a set of wheels and casters on which it is mounted by suitable levers, for easy locomotion. A capstan B with two rope or chain attachments *a a* is journaled in the 30 frame, as shown, the ropes or chains passing from the capstan over rollers C, C, for connection with the hoisting lever D. Loose bearers E, E', are supported on the frame, and carry the adjustable fulcrum brackets 35 F F'. The bearers E, E' can be adjusted in width apart to suit different kinds of work. Two pins *c c'* are loosely fitted to the holes of the brackets F, F'. The connection from the tree to be uprooted, to the

hoisting lever D is made at *e* between brackets F F'. In operating the capstan is applied to alternate ends of the lever D, and a fulcrum pin *c* to alternate brackets F F'. The raising of lever D on either side gives space for the insertion of pins *c* at a higher 40 point, so that by the application of the capstan to the hoisting of the lever at alternate ends, and the successive elevation of the fulcrum pin *c* in the brackets F F', a long range 45 of vertical motion, is given to the lever D for lifting purposes.

The principal use of the lever D is to start the larger stumps for which purpose the rollers C are applied in open bearings *g*, at the extremities of the frame as shown. 50 When greater speed and less power are required, the bearers E E', brackets F F' and lever D are removed and one of the rollers C applied in the central bearings G, a rope or chain being attached directly from the 55 capstan to the stump to be uprooted (see red lines Fig. 1).

An arm or sweep H is attached to the capstan, as shown, for the attachment of the motive power.

We claim as new and of our invention—
The combination and arrangement of the 65 capstan B, lever D and shiftable roller C; for applying the power at different speeds substantially as set forth.

In testimony of which invention, we hereunto set our hands.

WILLIAM KIMMEL.
DANIEL KIMMEL.
